UNITED STATES PATENT OFFICE

158,435

SOAP SUPPORT OR THE LIKE

Herman Biener, Brooklyn, N. Y.

Application February 23, 1949, Serial No. 1,032

Term of patent 14 years

(Cl. D4—3)

To all whom it may concern:

Be it known that I, Herman Biener, a citizen of the United States of America and a resident of Brooklyn, county of Kings, and State of New York, have invented a new, original, and ornamental Design for a Soap Support or the like, of which the following is a specification, reference being had to the accompanying drawing, forming part thereof, in which:

Fig. 1 is a face view of a soap support;

Fig. 2 is a side view thereof; and

Fig. 3 is a plan view.

I claim:

The ornamental design for a soap support or the like, as shown.

HERMAN BIENER.
